CLAIM

(21) Appl. No.: **29/403,305**

The ornamental design for a standard, handicapped accessible portable voting booth, as shown and described.

(22) Filed: **Oct. 4, 2011**

DESCRIPTION

(51) LOC (9) Cl. **06-03**

FIG. 1 is a front perspective view of the standard, handicapped accessible portable voting booth of the instant invention;

(52) U.S. Cl. **D6/421**

FIG. 2 is a front view thereof;

(58) Field of Classification Search D6/419-428,

FIG. 3 is a rear view thereof;

D6/429, 487; 312/194-196, 198, 6, 262;

FIG. 4 is a right side view thereof;

108/50.01, 50.02, 60; 235/51, 50 R; 52/36.1,

FIG. 5 is a left side view thereof;

52/36.4

FIG. 6 is a top view thereof;

See application file for complete search history.

FIG. 7 is a bottom view thereof; and,

(56) **References Cited**

FIG. 8 is a perspective view of multiple standard, handicapped accessible portable voting booth of the instant invention in a nested configuration.
